UNITED STATES PATENT OFFICE.

WILLIAM G. WILLCOXEN, OF QUINCY, ILLINOIS.

RAILWAY-SWITCH.

SPECIFICATION forming part of Letters Patent No. 687,361, dated November 26, 1901.

Application filed April 9, 1901. Serial No. 55,026. (No model.)

To all whom it may concern:

Be it known that I, WILLIAM G. WILLCOXEN, a citizen of the United States, residing at Quincy, in the county of Adams and State of Illinois, have invented certain new and useful Improvements in Railway-Switches; and I do hereby declare the following to be a full, clear, and exact description of the invention, such as will enable others skilled in the art to which it appertains to make and use the same.

This invention relates to railway-switches, and has special reference to that type commonly known as "double-track" switches, which are also applicable to single-track use for siding and heading-in purposes.

To this end the invention contemplates a novel construction of switch which entirely obviates the facing of the points of the switch-rail now ordinarily used, thus making an absolutely safe switch. A further object of the invention is to so arrange the switch-rails with reference to the separate track-rails co-operating therewith as to provide for firmly bracing and locking the switch-rails in their adjusted position, so as to absolutely prevent lateral shifting or movement thereof except through the medium of the operating devices constituting a part of the invention. In this connection the invention also has in view the provision of perfectly flush miter or bevel joints between the points of the switch-rails and the track-rail terminals associated therewith, so that a perfectly smooth track is provided for the train when guided by the switch-rails over the main track or onto the siding.

With these and other objects in view, which will more readily appear as the nature of the invention is better understood, the same consists in the novel construction, combination, and arrangement of parts hereinafter more fully described, illustrated, and claimed.

The essential features of the invention involved in the laterally and vertically movable switch-rails and the operating devices utilized in connection therewith are necessarily susceptible to a variety of modifications without departing from the spirit or scope of the invention, but the preferred embodiment of the improvements is shown in the accompanying drawings, in which—

Figure 1 is a plan view of a railway-switch

constructed in accordance with the present invention, showing the switch-rails in one position. Fig. 2 is a similar view showing the switch-rails in a different position. Fig. 3 is a side elevation of the switch, showing the points of the switch-rails elevated to clear the same from the terminals or points of the fixed track-rails to permit of the lateral shifting of the switch-rails. Fig. 4 is a detail sectional view on the line 4 4 of Fig. 2. Fig. 5 is a similar view on the line 5 5 of Fig. 2. Fig. 6 is a detail sectional view on the line 6 6 of Fig. 2.

Like characters of reference designate corresponding parts in the several views of the drawings.

In carrying out the invention the switch may obviously be employed for single or double track purposes, though possessing special utility as a double-track switch, so for illustrative purposes Figs. 1 and 2 of the drawings particularly illustrate the use of the switch for heading in, the darts indicating the direction of movement of the train that is guided by the switch-rails.

Referring particularly to the construction and arrangement of parts shown in the drawings, the reference-letters A A and B B designate, respectively, the fixed track-rails of the separate tracks with which the switch-rails C C co-operate, and for convenience in understanding the invention the rails A may be designated as the "main-track" rails, while the rails B may be termed the "siding" or "side-track" rails; but in all forms of the invention these rails may be fixed or rigid, while the switch-rails C are movable with relation thereto to provide for guiding the train either straight over the main track or off onto the siding B B.

The track-rails are secured to the cross-ties 1 in any approved manner, but the terminals of the adjacent portions of the rails A and B are preferably held rigid upon the ties in properly-spaced relation through the medium of double rail-chairs or tie-plates 2, securely spiked to the ties and provided with a pair of rail-seats 3 to respectively receive the separate rails A and B, and these double rail-chairs 2 may be placed upon the adjoining ties upon which rest the adjacent terminals of the fixed rails A and B.

The adjacent spaced terminals of the fixed

track-rails A and B may be additionally designated by the reference-numeral 4, and these terminals are arranged in a common transverse plane and are provided upon their inner sides with the mitered or beveled faces 5, which are also rabbeted or shouldered, as at 6, and are designed to register flush with the complementary mitered or beveled side faces 7 of the points 8 of the swinging switch-rails. 5 These side faces of the switch-rail points are also rabbeted or shouldered, as at 9, it being noted that the rabbets or shoulders 6 of the fixed rails form seats for the extreme tips of the switch-rail points, and vice versa, so that 10 when the switch-rail points are in register with the terminals of the fixed rails perfectly flush miter or bevel joints are provided. In connection with the miter or bevel faces of the fixed track-rails and of the switch-rails 15 it is to be observed that the same are provided upon the inner sides of the track-rails and upon the outer side of the switch-rails, so that the points of the switch-rails are just the reverse of the switch-rails commonly in use. 20 On account of the transverse alinement of the spaced terminals of the fixed track-rails it is necessary to provide a compound movement for the switch-rails to permit of the necessary switching or adjustment thereof. To 25 admit of this compound movement of the switch-rails, the same are connected at their relatively-fixed ends opposite the points 8 thereof by means of a suitable pivotal or loose coupling 10 to the contiguous ends of 30 the main-track rails, said couplings serving to permanently unite said ends of the switch-rails to the main-track rails, while at the same time allowing a vertically-swinging and laterally-shifting movement for the switch-rails. 35 The two switch-rails C C are connected together for movement in unison preferably through the medium of a plurality of tie-braces 11, pivotally connected at their ends, as at 12, with brackets or equivalent projections 13 at the inner sides of the switch-rails, 40 thus holding the same properly spaced and permitting of the free lateral movement thereof. 45

The vertical up-and-down movement of the switch-rails is accomplished through the medium of a raising and lowering device 14, preferably in the form of a transverse rock-shaft having a long crank or bend 15, extending transversely beneath the swinging portions of the switch-rails and slidably engaging within keepers or loops 16, provided at the under side of the switch-rails. The opposite journal portions 17 of the transverse crank-shaft are journaled in the angled bearing-plates 18, bolted or otherwise suitably fastened to the opposite ends of a cross-tie, and at one end the said crank-shaft is provided with an operating-lever 19, which provides for the rocking of the shaft and the 55 raising and lowering of the crank 15 thereof,

which causes a consequent raising and lowering of the switch-rail points.

The lateral shifting of the switch-rails C is provided for by a shifting device 20, preferably in the form of a vertical rock-shaft 21, 70 journaled in vertically-aligned bearings 22, fitted to an upright supporting-post 23, arising from one of the cross-ties, and provided at an intermediate point with an offset vertically-disposed crank 24. At its upper end 75 the rock-shaft 21 is provided with a horizontally-arranged handle 25, and the crank 24 thereof has pivotally connected therewith one end of a link 26, the other end of which is pivoted to a coupling 27, bolted or otherwise 80 suitably fastened to one of the switch-rails.

To provide for shifting the position of the switch-rails from one set of fixed track-rails to the other, it is first necessary to elevate the points of the rails through the medium of the 85 raising and lowering device 14, so as to clear the terminals of the fixed rails, and then by manipulating the shifting device 20 the points of the switch-rails may be moved laterally into position for registering engagement with 90 the mitered terminals of the fixed track-rails. When thus interlocked, on account of the reverse disposition of the miter-faces of the switch-rails and the fixed track-rails, lateral movement or displacement of the switch-rails 95 is impossible.

Changes in the form, proportion, and minor details of construction may be resorted to without departing from the spirit or sacrificing any of the advantages of the invention. 100

Having thus described the invention, what is claimed as new, and desired to be secured by Letters Patent, is—

1. In a railway-switch, the combination of the fixed track-rails having spaced terminals 105 in the same transverse plane, said rail-terminals having at their inner sides mitered faces, and shiftable switch-rails having mitered faces at the outer sides of their points which are complementary to those of the fixed 110 rails.

2. In a railway-switch, the combination of the fixed track-rails having spaced terminals in the same transverse plane, and vertically-movable and laterally-shiftable switch-rails 115 having their points extending into the transverse plane of said fixed rails.

3. In a railway-switch, the combination of the fixed track-rails having spaced terminals in the same transverse plane, said terminals 120 having at their inner sides rabbeted mitered faces, vertically-movable and laterally-shiftable switch-rails having complementary rabbeted mitered faces at their outer sides, a raising and lowering device coöperating with 125 the swinging portions of the switch-rails, and a separate shifting device also connected with the switch-rails.

4. In a railway-switch, the combination of the fixed track-rails having spaced terminals 130

in the same transverse plane, vertically-mov-
able and laterally-shiftable switch-rails hav-
ing their points extending into the transverse
plane of said fixed rails, a transverse rock-
5 shaft having a lever, and an extended crank,
the latter slidably engaging with the under
side of the switch-rails, a vertically-arranged
rock-shaft having a crank, and a link con-

nection between the crank of the rock-shaft
and the switch-rails.

In testimony whereof I affix my signature
in presence of two witnesses.

WILLIAM G. WILLCOXEN.
